UNITED STATES PATENT OFFICE

CHARLES P. LINDLEY, OF WATERBURY, CONNECTICUT.

IMPROVEMENT IN LANTERN-GLOBES.

Specification forming part of Letters Patent No. 38,754, dated June 2, 1863.

To all whom it may concern:

Be it known that I, CHARLES P. LINDLEY, of Waterbury, New Haven county, Connecticut, have invented, made, and applied to use certain new and useful Improvements in the Construction of Globes for Lanterns; and I do declare the following to be a full, clear, and correct description of the same, reference being had to the accompanying drawings, and to the letters of reference marked thereon, in which—

Figure 1 is a view of my improved globe for lanterns, when the same is provided with the opening and lip; Fig. 2, a view of the same when provided with the opening, but not the lip; Fig. 3, a view of the same when provided with the solid bottom and air-holes; Fig. 4, a view of the globe and reflector combined, the reflector being opened; Fig. 5, a detached view of reflector; Fig. 6, a view showing my improved globe as combined with the base and top of an ordinary lantern.

Like parts of the invention are indicated by the same letters of reference in the drawings.

The nature of my invention consists, first, in the construction of a globe of glass for lanterns, which globe shall be provided with the opening *a*, for the purpose of allowing the lamp placed within said globe and at the bottom of the lantern to be filled, trimmed, and regulated without the necessity of removing the same from the lantern; second, in providing said opening *a* with the projecting lip *b*, for the purpose hereinafter shown; third, in combining with a globe for lanterns provided with the opening *a* the reflector *C*, for the purpose or purposes hereinafter set forth; fourth, in providing a globe for lanterns having an opening, as at *a*, with a solid bottom and the air-holes, as fully described.

To enable others skilled in the arts to make and use my invention, I will speak of its construction and operation.

A shows an improved globe for lanterns, which globe, in process of manufacture, is provided with the opening *a*. This opening *a* is, in some cases, provided with the lip *b*, projecting outward, over which lip *b* the ring *B*, provided with the reflector *C*, fits snugly, and is held firmly in position by putty, cement, or in any ready manner.

B is a metallic ring, corresponding in size to the opening *a* in the globe, or made to fit snugly over the lip *b*. This ring *B* has hinged to it the reflector *C*, made of metal or any

suitable material, metal being generally used.

D shows the bottom of an ordinary lantern, within which the lamp *d* is placed, and *E* the top of the ordinary lantern, provided with the air-openings *e*.

In Fig. 3 a view of a globe provided with a solid bottom, *D²*, is shown, in which case the air-openings *e²* may be inserted on the side or in the bottom *D²*.

My improved globe for lanterns, being thus constructed, is inserted in the bottom *D* of the lantern, and held there by means of putty or cement in such a manner that the opening *a* shall be directly behind the flame of the lamp. The top of the lantern is placed over the top of the globe and held in position by putty or cement.

The object of my invention is to allow the party using the same to fill, trim, light, and extinguish the lamp without the necessity of removing it from the lantern, while the reflector serves not only as a door, which can be opened and shut at pleasure, and, when closed, excludes the air from the flame within, but also as a reflector.

For railroad-cars, for the use of railroad conductors, employés, and all parties using lanterns my invention will be found particularly valuable, on account of the strong light thrown by it and the readiness with which the lamp can be attended to and the necessity of not removing it from the lantern. In case of stormy or windy weather this latter consideration will be found especially valuable.

While in the present instance I have shown a reflector of concave shape, I do not intend to confine myself to it, as I am well aware that a convex, or even a plane, surface may be employed.

Having thus described my invention, what I claim as new, and desire to secure by Letters Patent, is—

1. Providing a lantern-globe with an opening, *a*, for the purpose specified.
2. In combination with the same, the lip *b*, for the purpose described.
3. In combination with the globe provided with the opening *a*, the use or employment of the reflector *C*, or its equivalent, for the purpose herein set forth.

CHARLES P. LINDLEY.

In presence of—

C. C. GORDON,
J. PAUGE.
